UNITED STATES PATENT OFFICE.

PAUL MARIE THÉODORE IMBAUD, OF AMBARES, FRANCE.

BOTTLE-STOPPER.

SPECIFICATION forming part of Letters Patent No. 519,910, dated May 15, 1894.

Application filed December 30, 1893. Serial No. 495,177. (No model.) Patented in France December 17, 1892, No. 226,457; in Belgium June 14, 1893, No. 105,090; in England June 17, 1893, No. 11,968, and in Italy June 30, 1893, No. 34,279.

To all whom it may concern:

Be it known that I, PAUL MARIE THÉODORE IMBAUD, proprietor, a citizen of the French Republic, residing in Ambarès, (Gironde,) France, have invented certain new and useful Improvements in Stoppers for Bottles, (for which I obtained a patent in France December 17, 1892, No. 226,457; in Belgium June 14, 1893, No. 105,090; in Great Britain June 17, 1893, No. 11,968, and in Italy June 30, 1893, No. 34,279,) of which the following is a specification.

My invention relates to improvements in stoppers for bottles containing effervescent or still liquids, and its object is to provide a convenient means for permitting the withdrawal of liquid from time to time without allowing the escape of gas or evaporation of liquid at such times as the liquid is not being withdrawn. I attain these objects by the construction illustrated in the accompanying drawings, in which—

Figure 1 is a sectional elevation showing the general construction of my improved stopper; Fig. 2 being a plan of the same, and Fig. 3 a back elevation.

Similar letters refer to similar parts throughout the several views.

The body of the stopper consists of a hollow tube E at the lower part, to be inserted in the neck of the bottle, and a hollow rubber plug B thereon for adapting it to various sizes of necks of bottles. On the interior of this plug are formed annular grooves e of increasing sizes to facilitate compression and insure the soundness of the joint. The tube E is provided at its upper extremity with a shoulder c which abuts against the top of the india-rubber plug. Above the tube the body of the stopper is formed in two parts A A', screwed or otherwise joined together, the upper portion being furnished with a beak or mouth-piece h for the outlet of the liquid, and through which extends the rod T provided with a button t on its upper end, and with a valve t³ at its lower end, arranged to be operated by means of a spiral spring r as shown. The valve t³ is preferably furnished with a washer of india rubber for the purpose of insuring a tight joint when the valve is closed. The chamber A is perforated at any convenient place on the side opposite the mouth-piece a with a small hole

b to allow access of air, and the chamber A' is provided externally with a forked nipple 55 or hook g on one side and with a stud h on the other side to permit, in the case of effervescent water, the wire originally used for retaining the cork, after it has been cut, to be conveniently twisted round this hook and 60 stud and so retain the stopper in position. As shown in Fig. 1, a cork-screw D is hinged at d to the portion A' of the body, and this body has secured to it at any convenient part, a brush i to clean the neck of the bottle after the cork has been drawn. 65

I claim as my invention—

1. A stopper for bottles consisting of a tube to enter the neck of the bottle, a body above the tube, provided with a valve adapted to 70 be opened from the outside, an outlet above the valve, the said body being also provided on the outside with a stud on one side and a hook on the other, the said stud and hook adapted to engage with the wires, which 75 have served to fasten the cork for transportation, to bind the stopper to the bottle, all substantially as set forth.

2. A stopper for bottles consisting of a tube to enter the neck of the bottle, a body above 80 the tube, an external shoulder being formed between the body and the tube, a hollow rubber plug provided with internal annular grooves on the tube and abutting against the said shoulder, the said body being provided 85 with a spring-actuated stem-valve adapted to be opened from the outside, an outlet above the valve, and a stud and a hook on opposite sides of the body as and for the purposes set forth. 90

3. A stopper for bottles consisting of a tube to enter the neck of the bottle, a hollow rubber plug on the tube, and a body above the tube provided with a spring-actuated stem-valve, a beaked outlet above the valve and a 95 stud and hook on opposite sides of the body, the said stem valve being provided with an operating button, substantially as and for the purposes set forth.

In testimony whereof I have signed my 100 name to this specification in the presence of two subscribing witnesses.

PAUL MARIE THÉODORE IMBAUD.
